UNITED STATES PATENT OFFICE

MAURICE J. PECK, OF PUEBLO, COLORADO, ASSIGNOR, BY DIRECT AND MESNE ASSIGNMENTS, TO AMERICAN SAFETY DEVICE COMPANY, OF PUEBLO, COLORADO, A CORPORATION OF COLORADO

SAFETY ATTACHMENT FOR MOVING PICTURE MACHINES

Application filed June 11, 1930. Serial No. 480,440.

This invention relates to moving picture mechanism and analogous means utilizing a combustible film, and particularly pertains to automatically operating safety devices in connection with the magazines and which, in an emergency, are instantly or simultaneously and automatically brought into operation to sever that portion of the film exterior of the magazines and prevent firing of the portions of the film contained within the magazines.

The invention further contemplates the provision of automatically operating safety devices in connection with the magazines of moving picture mechanism whereby the film is severed in the event of firing of the portion thereof which extends between the magazines, to prevent ignition of the remaining portion of the film in the magazines, and at the same time, or instantly with the severing of the film, cause the motor to cease operation and extinguish the lighting means of the projector.

The invention consists in the construction and arrangement of the several parts which will be more fully hereinafter described and claimed.

In the drawings:

Fig. 1 is a sectional view through portions of upper and lower magazines of a moving picture mechanism and illustrating parts of the film which run between the magazines, or which feed from one to the other, together with the safety devices embodying the features of the invention, the feeding devices being shown set for operation.

Fig. 2 is a sectional view of a portion of one of the magazines and one of the safety device organizations in connection therewith, the parts of the safety device organization being shown released.

Fig. 3 is a top plan view of a reciprocating film severing knife plate, showing the film in horizontal section and devices cooperating with the plate illustrated in dotted lines.

Fig. 4 is an enlarged transverse vertical section through interlocking levers and an inflammable loop or tie thereover, together with an inflammable pendant or leader which serves, when ignited and consumed, to release the said levers.

Fig. 5 is a horizontal section through the inflammable loop and tie and an electrical attachment for effecting an ignition and consumption of the loop or tie under certain conditions, the locking levers being shown engaged by the tie in full and dotted lines.

Fig. 6 is a wiring diagram of the circuits involved.

A and B respectively designate the lower and upper magazines usually embodied in moving picture mechanism, the lower magazine having guide rollers 5 at the base of a throat 6 in line with a slot 7 in the top 8. The upper magazine B has an inclined throat 9 depending from a slot 10 in the bottom 10^a, a guide roller 11 being adjacent to said slot and the guide rollers 12 being disposed below the lower end of the throat 9, below which guide rollers is a further guide roller 13 in cooperative relation to a feed sprocket 14 driven by a motor as usual in machines of this class. Each of the magazines A and B is adapted to contain a suitably mounted and actuated reel, as will be readily understood. Rising above the slot 7 in the top 8 of the lower magazine A is an upwardly extending exterior throat 15, which is practically a continuation of the throat 6 below said slot. The film 17 is fed through the throats 6 and 15 and passes between upper guide rollers 18 and then across the open space between the lower and upper magazines for projection purposes, as is customary in moving picture mechanism.

On the lower side of the top 8 of the magazine A are guiding or grooved devices 19 in which is mounted a sliding plate 20 of the form shown by Fig. 3 and having a slot 21 extending from one side edge partway across the width thereof, the one wall 22 of the slot being beveled and formed as a cutting edge or knife. The same form of slide plate 20 is associated with the bottom of the upper magazine B as indicated at 23, the latter plate moving in grooved guides 24 and having a slot and knife edge in all respects similar to the slot 21 and knife edge 22 as shown in Fig. 3. In other words, the plates 20 and 23 are duplicates in construction and are held within the respective magazines A and B.

- The plates 20 and 23 are shiftable to close the slots 7 and 10 of the magazines, and, when the plates 20 and 23 are set for operation, the slots 21 thereof are located over or coincident with the slots 7 and 10, to permit the film to pass therethrough. At one end of each plate 20 or 23 a retractile spring 25 is secured to the center thereof and operates to draw the plate to which it is connected across the slot controlled by the said plate. At the extremity of each plate 20 or 23, opposite that to which the spring 25 is secured, an opening 26 is formed in line with the point of attachment of the said spring 25, the latter being secured to either the top of the lower magazine A or the bottom of the upper magazine B, as clearly shown.
- The automatically operating mechanism controlling the release of either plate 20 or 23 is associated with each magazine, being arranged on the top 8 of the lower magazine A and depending from the bottom 10^a of the upper magazine B. This automatic mechanism is reversed in its application to the lower and upper magazines A and B but the elements thereof are precisely the same and a description of one will suffice for both and similar reference characters will be applied to corresponding parts.
- Projecting upwardly from the top 8 of the lower magazine A and downwardly from the bottom 10^a of the upper magazine B is a fulcrum bracket 27, to the free end of which a catch lever or jaw 28 is fulcrumed between its ends, which lever has at its inner end a projecting nose 29. To the outer end of the catch lever or jaw 28 is pivotally connected a latch post 30, which projects through a suitable opening 31 in the adjacent side of the magazine and terminates in a rounded head 32 to engage the opening 26 of the plate 20 or 23. On the latch post 30 a spring 33 is mounted and secured at one end to said post and bears against the adjacent side of the magazine for the purpose of assisting in quick disengagement of the latch post 30 from the opening 26 of either plate 20 or 23 when the mechanism is automatically operated to release either one or both of the said plates, as will be hereinafter explained. Also secured to the adjacent side of each magazine is a switch box or enclosure 34 having therein a knife switch 35, pivoted at one end to a contact or connector 36 and movable into and outwardly from an opposing contact 37 in a manner similar to the ordinary knife switch construction. Each knife switch or blade 35 has the inner end of a lever or jaw 38 pivotally connected thereto, which lever or jaw is movable through an opening or slot 39 in the intermediate portion of the outer side of the switch box or casing 34. The outer free extremity of the lever or jaw 38 has a recess or notch 40 formed therein for the reception of the nose 29 of the complementary lever or jaw 28. On

the lever or jaw 38 is a spring 41, secured at one extremity to the latter lever or jaw and bearing at its opposite extremity against the side of the switch box or casing 34 adjacent the opening or slot 39 therein and tending to move the jaw longitudinally in a direction to close the switch 35. The lever or jaw 28 also has an auxiliary retractile spring 42 secured thereto and to an adjacent portion of the side of the magazine and operating to positively separate the lever or jaw 28 from the lever or jaw 38 when the said jaws are released. Each of the contacts 36 and 37 of the respective switches has electrical wire connections 43 and 44 attached thereto and also adapted to be connected to a magnetic switch c (shown diagrammatically in Fig. 6) which, when actuated, breaks the electric circuit to the motor and lighting means of the projector and thus automatically stops the operation of the motor and extinguishes the said lighting means.

Fusible means are provided for holding the noses 29 of the levers 28 in the notches 40 of the levers 38 and which, when the film is ignited, may burn away to release said levers. This fusible means comprises a loop 45 of celluloid or other analogous, quickly inflammable material, shown on an enlarged scale in Figs. 4 and 5, the said loop being of such dimensions as to fit over and hold together the engaged free ends of the levers or jaws 28 and 38. To each loop or sleeve 45 of inflammable material is secured one end of a pendant or projecting strip 46 of the same material, which terminates within igniting adjacency to the looped portions of the film 17, the free end of the strip 46 associated with the upper magazine being opposite to the free end of the strip 46 associated with the lower magazine, as clearly shown by Fig. 1. Secured to each loop or sleeve 45 is a casing 47, preferably of porcelain, having therein a high resistance wire or coil 48 with which a portion of the loop or sleeve 45 is in contact. The terminals of the high resistance coil 48 associated with the upper magazine are connected by wires 49 and 50 to the terminals 36 and 37 of the switch 35 associated with the lower magazine, and the high resistance coil 48 associated with the lower magazine are connected to the terminals 36 and 37 of the switch 35 associated with the upper magazine. Therefore when the film is ignited adjacent one of the strips 46 it will ignite and burn away such strip and its associated loop 45 and thus release the ends of the levers 28 and 38, which are held together by such loop. This will permit the spring 42 to rock the lever 28 and thus withdraw the head 32 of the latch post 30 from the opening 26 of the sliding plate 20 or 23 and permit such plate to close the slot 7 or 10 with which such plate is associated and also permit the associated switch 35 to close. The closing of the switch 35

will permit electric current to flow through the wires 51 and 52 or 53 and 54 to the high resistance coil 48 associated with the other loop 45 to heat said coil and ignite and burn away the latter loop and permit the sliding plate 20 or 23 associated with the latter loop to close its associated slot 7 or 10 and also permit the switch 35 associated with the latter loop to close its associated slot.

5 The device is set for operation by shifting the plates 20 or 23 against the resistance of the springs 25 connected thereto and effecting an engagement of the rounded heads 32 of the latch posts 30 with the openings 26 in the 10 ends of the said plates opposite the points of attachment thereto of the springs 25. At the same time the projecting noses 29 of the levers or jaws 28 are caused to engage the notches 40 of the levers or jaws 38, thus opening 15 the switches 35 against the resistance of the springs 41. The engagement of the jaws or levers as just explained and the projection of the rounded ends 32 of the latch posts 30 into the openings 26 of the plates 20 or 23 20 will be effected against the resistance of the springs 33 and 42. The loops or sleeves 45 of inflammable material are then applied over the engaged extremities of the levers or jaws 28 and 38 and the pendants or projecting 25 strips 46 arranged in close or igniting adjacency to loops of the film 17. In the event of firing of the film, which may be due to various causes, the part of the film ignited nearest the one pendant or strip 46 will cause the 30 latter to ignite and consume and release the loop or sleeve 45 and permit the extremities of the levers or jaws 28 and 38 thereby to fly apart, closing the associated switch 35 and the electric circuit to the magnetic switch to actuate 35 said switch and effecting a stoppage of the motor and an extinguishment of the lighting means of the projector. When this operation ensues in connection with one set or group of the levers or jaws, the remaining set 40 is also instantly operated through the medium of the electrical connections explained, and as a consequence both plates 20 or 23 are released in view of the fact that the latch posts 30 have become disengaged therefrom and the springs 25 are free to act. Thus the 45 slots 7 and 10 of the respective magazines are closed and simultaneously the portion of the film exterior of the magazines is severed from the remaining portions of the film within the 50 magazines and on the reels of the latter are shielded against firing or ignition. The operation of the device is very simple and effective, and after the automatic operation as just described has ensued and the film 17 been re- 55 arranged for service, the safety attachments may be again reset as shown by Fig. 1. When the groups of levers or jaws 28 and 38 are separated, they assume the positions shown by Fig. 2, and it will be seen from this figure that 60 the plate 23, for example, has been shifted to

close the slot 10 and throat 9. The same operation will take place in connection with the lower magazine A.

What is claimed as new is:

1. In a moving picture machine embodying film magazines having openings in adjacent sides for movement of the film therethrough from one magazine to the other, and knife plates automatically shiftable with relation to said openings, automatically operating means normally holding said plates in open position and permitting them to shift relatively to said openings when the film is ignited, said means comprising an electrical switch associated with each magazine and having a movable member and contacts and a jaw movably secured to said movable member and a jaw pivoted to the adjacent magazine side and extending toward the jaw of said switch, the latter jaw having means for locking the plate of its associated magazine open, fusible means embodying a high resistance coil surrounding the engaged extremities of said jaws and having a portion extending into igniting adjacency to a portion of the film, and electrical connections between the contacts of each of said switches and the high resistance coil of one of said fusible means.

2. In a moving picture machine embodying film magazines having openings in adjacent sides for movement of the film therethrough from one magazine to the other, and knife plates automatically shiftable with relation to said openings, means associated with each plate for holding said plate in open position and operable when the film is ignited to permit said plate to shift to closing position, said means comprising an electrical switch having a movable member and contacts and a jaw movably secured to the switch member, a second jaw pivoted to the adjacent magazine side, said second jaw having means for locking the plate of its associated magazine in open position, fusible means including a high resistance heating coil surrounding the engaged extremities of said jaws and having a portion extending into igniting adjacency to a portion of the film, and electrical connections between the contacts of each of said switches and one of said fusible means, for simultaneously operating the similar mechanisms in connection with each magazine.

3. In a motion picture machine embodying film magazines having openings in adjacent sides for movement of the film therethrough from one magazine to the other, and knife plates automatically shiftable with relation to said openings, automatic means for holding each of said plates in open position and permitting it to shift relatively to and to close its associated opening, said means comprising a switch having a movable member and contacts and interfitting jaws re-

spectively movably secured to the switch member and the adjacent magazine side, said jaws normally extending toward and engaging each other the one jaw having means 5 for locking one of said plates in open position, fusible means including a heating coil surrounding the engaged extremities of the jaws and having a portion extending into igniting adjacency to a portion of the film, 10 and electrical connections between the contacts of each of said switches and the heating coil of one of said fusible means, and means actuated by said switches for breaking the electric circuits to the motor and to the 15 lighting means of the projector.

4. In a moving picture machine embodying film magazines having openings in adjacent sides for movement of the film therethrough from one magazine to the other, and 20 knife plates automatically shiftable with relation to said openings, automatic fuse controlled means associated with each of said plates for normally holding said plates in open position and, when actuated, permitting 25 them to shift into closing position, each of said means comprising a switch having a movable member and contacts and engaging jaws respectively movably secured to the switch member and to the adjacent magazine 30 side, the one jaw having means movably attached thereto for locking one of said plates in open position, fusible means including a heating coil surrounding the temporarily engaged extremities of the jaws and having 35 a portion extending into igniting adjacency to a portion of the film, and electrical connections between each of said switches and the heating coil of one of said fusible means, and means actuated by the closing movement 40 of said switches for effecting a stoppage of operation of the motor for the film and an extinguishment of the lighting means for the projector.

5. In a moving picture machine embodying a pair of film magazines, each having a throat for the passage of film therethrough to the other magazine and each of said magazines having associated therewith a knife normally tending to move across its throat 45 for severing the film, and a latch for holding said knife in retracted position and normally movable out of engagement with said knife, means for holding each latch in engagement with its associated knife and simultaneously releasable with the latch holding means of the other magazine when the portion of the film external to said magazines is ignited, said means comprising an electric switch normally movable into closed position, a fusible member directly engaging 50 said latch and said switch to hold the latch in engagement with its associated knife and the switch in open position, an electrically heated element associated with each of said 55 fusible means, and an electrical circuit be-

tween each of said switches and the electrically heated element associated with the latch of the other magazine for heating such electrically heated element when said switch is closed.

In testimony whereof I have hereunto set my hand.

MAURICE J. PECK.
